UNITED STATES PATENT OFFICE.

JOHN F. HANLON, OF BOSTON, ASSIGNOR TO GEORGE O. HANLON AND JOSEPH P. A. HANLON, BOTH OF CAMBRIDGE, MASSACHUSETTS.

RAILWAY-RAIL.

SPECIFICATION forming part of Letters Patent No. 276,242, dated April 24, 1883.

Application filed October 5, 1882. (No model.)

To all whom it may concern:

Be it known that I, JOHN F. HANLON, a subject of Great Britain, residing at Boston, in the county of Suffolk, State of Massachusetts, United States of America, have invented a certain new and useful Improvement in Railway-Rails, of which the following is a description sufficiently full, clear, and exact to enable any person skilled in the art or science to which 5 said invention appertains to make and use the same, reference being had to the accompanying drawings, forming a part of this specification, in which—

Figure 1 is a side elevation; Fig. 2, a plan or top view; Fig. 3, a bottom view; Fig. 4, an isometrical perspective view, showing the parts of the joint detached; Figs. 5 and 6, vertical transverse sections of the rails, taken through the joint; and Fig. 7, a vertical transverse section taken through one of the fish-plate bolts. 15

Like letters of reference indicate corresponding parts in the different figures of the drawings.

My invention relates more especially to the 25 joint of the rail; and it consists in a novel construction and arrangement of parts, as herein-after more fully set forth and claimed, by which a more effective device of this character is produced than is now in ordinary use.

The nature and operation of my improvement will be readily understood by all conversant with such matters from the following explanation, its extreme simplicity rendering an elaborate description unnecessary. 30

In the drawings, A B represent the rails, which are of full thickness or rectangular in cross-section at the joint and connected in the usual manner by the fish-plate C and nuts and bolts d. The joint proper is formed as best 35 seen in Fig. 4, the rail B being provided with the horizontally-projecting flanges m x, and

with the V-shaped projection a, and the rail A with the rabbet g, space or mortise f, and V-shaped slot l, into which the projections x, m, and a respectively enter when the rails are 45 united, as shown in Fig. 1.

It will be obvious that in forming the spaces g f a flange, n, is necessarily produced, and that a corresponding slot or space, i, will be left in forming the flanges m x, in which the flange n 50 will rest when the rails are connected.

The object of the flanges m n is to unite the rails in such a manner as to prevent the depression of either without a corresponding depression of the other, thus always maintaining 55 an even rail at the joint and effectually preventing hammering.

The object of the V-shaped projection a and slot l is to prevent shunting or undue lateral movements of the rails at the joint, thus overcoming the danger arising from the rails spreading at this point. 60

It will also be obvious that in rails provided with my improved joint there is no especial necessity for the use of chairs. 65

The rail is also substantially continuous, as a car-wheel in passing from A to B will pass onto the V-shaped projection a before it leaves the rail A, and vice versa.

Having thus explained my improvement, 70 what I claim is—

The improved railway-rail joint described, the same consisting of the rails A B and plate C, the rail A being provided with the V-shaped slot l, spaces f g, and flange n, and the rail B with the V-shaped projection a, space i, and flanges m x, all constructed, combined, and arranged to operate substantially as specified. 75

JOHN F. HANLON.
